UNITED STATES PATENT OFFICE

MORRIS M. TITTERINGTON, OF BROOKLYN, NEW YORK; GEORGE A. TITTERINGTON, EXECUTOR OF SAID MORRIS M. TITTERINGTON, DECEASED, ASSIGNOR TO PIONEER INSTRUMENT COMPANY, INCORPORATED, OF BROOKLYN, NEW YORK, A CORPORATION OF NEW YORK

EARTH INDUCTOR COMPASS

Application filed May 21, 1925. Serial No. 31,742.

This invention relates to improvements in compasses, and more particularly to rotating coil, electric or earth inductor compasses, and is an improvement over the electric compass shown in former application Serial Number 5 542,937, filed March 11, 1922.

Some of the objects of this invention are to provide in such a compass, improved power or driving means for the potential generating element, the securing of indications in connection therewith, improved means for stabilizing the generating element, and providing an improved fieldless generator the commutator brushes of which are rotatably adjustable by a direction controller, and the latter instrument being novel in its compass dials arrangement. Other objects and advantages will appear as the invention is disclosed and described.

20 A further object is to produce an earth inductor compass mechanism or system which may conveniently be installed in or combined with the fuselage of an airplane with the various units of the compass system separated or remotely placed from each other to attain 25 the most efficient operation and accurate indications.

While a practical embodiment of this invention is shown in the drawings and disclosed in this specification, it will be understood that various modifications may be resorted to without departing from the spirit of the invention.

30 Referring to the drawings which represent one of the preferred forms of the invention:

Figure 1 represents the generator unit in longitudinal section; and Figure 2 represents an air-impeller drive head unit, also in section; these two views being aligned to represent the two units in assembled relation.

Figure 3 represents an electric motor drive head which is interchangeable with the air impeller drive head shown in Figure 2 for use in case it is desired to electrically drive the 45 compass generator.

Figure 4 represents a fragmentary sectional view on the line 4-4 of Figure 1, showing details of a universal joint and gimbal support by which the rotating armature is suspended from a drive shaft.

50 Figure 5 represents a plan view of the generator of Figure 1 with the drive head of Figure 2 mounted thereon.

Figure 6 is a front elevation of the direction controller with its graduated compass direction dials; and Figure 7 is a side elevation of the same controller with a fragment of the shaft control assembly attached thereto.

55 Figure 8 shows a plan assembly of the various units of the compass system installed in the fuselage of an airplane with the generating unit placed preferably back in the tail of the machine and the direction controller unit and deviation or steering indicator installed convenient to the pilot or observer.

60 Figure 9 is a front elevation of a meter employed as the deviation indicator or steering meter.

70 Referring more particularly to the drawings, the inductor generator for the compass system comprises an armature 11 and a commutator 13 both fixed on a shaft 12. The armature windings 11 are connected with the commutator in the usual way as indicated by the numeral 10. The armature shaft 12 is journaled in bearing 16 and 17, one of which forms part of an upper casing 18 and the other of which is attached to a lower casing 19. Carried upon the casing 19 are also the commutator brushes 20 and 21 which bear upon and collect current from the commutator 13.

80 Integral with the casing 18 are spaced upstanding lugs 22 and 23 by means of which the casing 18 is freely and movably suspended for universal movement from a gimbal ring 24 by the pin 25. The gimbal ring 24 is in turn suspended from lugs 26 and 27.

50

55

60

65

70

75

80

85

90

by means of pins 28, and the lugs 26 and 27 are formed integrally with and depend from a rotatable generator mounting base in the form of a worm wheel 31 which carries an integral upstanding bearing sleeve 30. The sleeve 30 is rotatably carried upon the lower end of an upstanding tubular member 32 which is secured to a base member plate 33 by means of which the generator is fastened to the vehicle represented in Figure 8 by an air airplane fuselage 34.

A nut 39 is screwed on the lower end of the tube 32 to support the worm wheel 31 and armature unit suspended therefrom. To the housing base plate 33 is attached a cover 35 which encloses that part of the mechanism which is below the base member 33. It will now be understood how the armature assembly and its closure casing 18—19 swings pendulously and universally free from the worm wheel 31 by placing the gimbal or other universally pivoted support 24 therebetween; and the gear 31 is rotatably adjustable on the lower end of the tube 32 which thus constitutes a rotatably adjustable support or mounting means from which the armature 11 is pendulously suspended and gyroscopically stabilized and by which the pilot or navigator may alter the position of the current collecting brushes 20 and 21 as later described for the purpose of obtaining indications of direction to enable him to steer the craft.

To the upper end of the armature shaft 12 is anchored a lower yoke 41 forming part of a universal joint which is shown in section in Figure 4. The yoke 41 is attached to a universal joint ring 42 by pivot screws 43 and to this ring 42 is also attached a second or upper yoke 44 by means of pivot screws 45. The upper yoke 44 is fastened to a short shaft 47 which is slidably connected to a driving shaft 46 which may be partially tubular. It is now understood how the universal joint 41—44, while not supporting the generator unit 11, is adapted to drive it and the universal joint is suspended concentrically through the gimbal support 24 and the horizontal axis of the universal joint and gimbal joint lie in a common plane.

Thus the generator is supported by the rotatable mounting gear base 31 and the armature is driven by transmission shaft means 46 extending through said gear down to the generator therebeneath, and the generator mounting means 31 is capable of manual adjustable turning movement so as to orient the brushes 20 and 21 around to a position in relation to the direction of the earth's flux where no current will be generated in the armature.

Two alternate means are provided for driving the shaft 46 and the generator armature 11, one electric and one by air pressure as will be illustrated.

A description of power means for driving the compass generator will now be given, and referring first to Figure 2, a housing 48 is carried upon the upper end of the tube 32. This housing 48 is clamped to the tube 32 by means of the bolt 49 and nut 50. By releasing the bolt and nut the housing 48 may be rotatably adjusted to any position upon the tube 32. Within this housing 48 is journaled the upper end of the drive shaft 46. At right angles thereto, a shaft 52 is journaled and bevel gears 53 and 54 are fastened to shafts 52 and 46 and to the forward end of shaft 52 is secured an air impeller 55. Air pressure from an airplane in flight spins the propeller 55 and thus drives the generator armature causing potential to be produced by virtue of the windings 11 cutting through the earth's magnetic field. The adjustable attachment between housing 48 and tube 32 makes it possible to turn the housing 48 and impeller 55 to a position where the impeller receives the greatest air pressure thereupon to drive the generator.

An alternate form of driving means, comprising an electric motor, is shown in Figure 3. In this form the tube 32 carries on its upper end the electric motor 61 and the shaft 46 is connected to and driven from the shaft of the electric motor.

Electric connections from the brushes 20 and 21 are made with wires 71 and 72 which wires are connected to slip rings 73 and 74 which are anchored on the bearing sleeve 30 but insulated from it by a bushing 75. Current is collected from these slip rings by contact brushes 76 and 77 which are in turn connected to transmission wires 78 and 79. These wires 78 and 79 establish electrical connection between the generator unit and a steering meter or deviation indicator 9 located any suitable distance from the generator, as in Figure 8, the wires 78 and 79 usually being mounted on the frame of the fuselage when the compass system is installed in an airplane. The face of the deviation or steering meter or galvanometer 9 is shown in Figure 9 which is also illustrated its deviation indicating hand 80 which normally points to zero on the dial of the indicator 9 when the airplane is traveling in the direction indicated on the graduated compass dials 106 and 107 of the manually operable direction controller 6.

A mechanical connection or transmission drive means is established between the generator and direction controller and to this end, an operating shaft 87 is journaled in the base member casing cover 33 and carries a worm 86 which engages the worm wheel 31. This shaft extends through the cover 35 and carries on its outer end a universal joint 88 to which is attached a piece of shafting 89 by any appropriate means. This shaft is connected through bearing blocks 91 and

chored to the fuselage 34 and to a miter gear box 92 which is in turn connected to the direction controller 6. A front view of this controller is shown in Figure 6 and a side elevation in Figure 7. Bearing blocks 91, miter gear box 92, and direction controller 6 are equipped with universal joints as shown. The gear transmission 31-86 holds the generator, particularly its commutator brushes, against displacement and in that respect is a locking means which releases when the controller and transmission is operated.

The direction controller 6 comprises an operating shaft 96 journaled within the case 6 and which may be turned by controller drive means such as a handle 97. Through bevel gears fixed to shaft 96 and 99 within the controller housing 98, the shaft 99 and universal joint 100 are turned by the handle 97. To the universal joint 100 is connected a piece of shafting 101 by means of a clamp 102 or other suitable means. This sectional shaft 101 installed on the fuselage forms part of the shaft line connected with shaft 89 on the generator already mentioned and by which a mechanical operating connection is established over an angular course between the direction controller 6 and the generator.

A direction indicating compass dial 106 is graduated from 0 to 9 as shown and this dial is fixed to the controller shaft 96 so that the dial makes one complete turn for every turn of the crank 97 and the dial is exposed to view on the front face of the direction controller case 6 in which the dials are mounted. Geared to this dial 106 in a ratio of 1 to 36, in a second concentric compass dial 107 which is graduated from 1 to 36 or N corresponding to a compass card graduated in 10° intervals. The two compass dials are availed of to provide a fine compass setting since one dial may be used as a vernier to read against the other dial and this arrangement aids a navigator in laying out and following a precisely defined course.

Having described a structural embodiment of this invention, its operation will now be explained.

The various units are installed on an air-craft or other vehicle as illustrated in Figure 8. The direction controller 6 and the steering or deviation indicator 9 are usually installed on the instrument board 90 remotely from the generator and in plain view of the pilot or navigator.

The inductor generator is placed in operation by the rotation of the air impeller 55 or the electric motor 61. As the armature 11 is rotated, the wires comprising it are caused to cut the earth's lines of force and a potential is generated. As in any electric generator, the external potential depends upon the relation between the position of the collecting brushes and the direction of the field flux.

If therefore the brushes 20 and 21 are

oriented, by turning the direction controller handle 97, and through the shaft line 101 and worm 86 the worm wheel 31 and dependent parts, two positions of the brushes will be found where the external potential reads zero on the steering meter 9.

When a null indication of the meter 9 shows that the brushes 20 and 21 are in a position of zero potential, the mechanical connection, in first installing the system for service, between the direction controller 6 and generator 11 is broken by disconnecting the shaft line 101. The controller handle 97 is then turned until the compass dials 106-107 indicate the direction in which the vehicle is headed. The mechanical connection 101 is then re-established and the controller is rotated a few degrees to the right or left. If now the hand 80 of the deviation or steering meter 9 moves in the same direction as the controller dials 106-107 have been turned, the electrical connection 78-79 between the generator and meter 9 is correct and may be made permanent. If the meter moves in a direction opposite to that in which the controller compass dials 106-107 was rotated, the connections of wires 78 and 79 to the steering meter must be reversed in order to properly complete the assembly and make it ready for service.

The operation of the compass consists in setting upon the compass dials 106 and 107, the direction in which it is desired to navigate the craft. This is accomplished by manually turning the direction controller crank 97 until the dials are brought into proper relation with the lubber's line. If the direction or steering meter hand 80 indicates zero, the craft will be headed in the direction indicated by the direction controller dials or else in a direction the exact reverse thereof. To determine in which of the two directions the craft is headed, said craft is steered slightly to the right or left. If now the meter hand 80 indicates by moving in the same direction as the craft is steered, the heading is that indicated on the dials 106-107 of the direction controller 6, but if the meter hand 80 moves off of zero oppositely to the direction in which the craft is steered, the said craft is then known in fact to be headed in a direction the reverse of that shown on the controller dials and the direction of travel is accordingly corrected by reversing the direction of the craft.

One of the improved features among others of this invention is the gimbal ring suspension 24 for pendulously supporting the non-rotating housing 18 containing the revolving armature 11 together with the substantially concentric universal joint 41-44 connecting the driving shaft 46 and the armature shaft 12 and which joint is disposed down through the gimbal suspension ring 24. This permits the mechanical driving of the

armature without interfering with its pendulous suspension and permits the generator to hang vertically and to stabilize itself so as to properly operate in relation to the earth's flux lines. This improved structure permits the fuselage to roll or pitch without disturbing the operating efficiency or position of the generator stabilized in the earth's flux, it being desirable to maintain the generator in a predetermined position to eliminate errors in generation otherwise introduced by the vertical component of the earth's flux.

My improved airplane and compass combination shown in Figure 8 is particularly useful because the generator is placed back in the tail of the airplane where its operation is not hindered by outside electrical or magnetic disturbing influences such as would occur in case the generator was placed near the instrument board for in the latter case other instruments on board the craft would interfere with the free and normal potential output of the compass generator. The universal shaft-line connection 101 running from the instrument board 2 to the rotary generator mounting base 31 along the airplane fuselage frame 34 and forming part of the combined system, enables the manufacturer to very conveniently locate the generator and direction controlled as far apart as he may wish, and at the same time the compass controller dials 106—107 are interconnected with the inductor generator brushes 20 and 21 so that these parts turn together and the direction in which the vehicle is headed is shown by the compass dials at the instant that the deviation indicator hand 80 points to 0.

It is significant that the commutator brushes 20 and 21 are carried by or with orientable brush mounting means such as the wheel 31 gear driven by the small pinion 86. The brushes are suspended, in this instance by the case 19, from the turntable gear or orientable mounting means 31 and bear against the commutator 13 and are subject to orientation thereabout by the operating means 101 which is driven by the controller drive means 97 and by which a dead or non-potential position is found for the brushes. It is of course preferred that the armature be stabilized so as to normally function in the earth's field and as a matter of structural convenience it is also suspended in this instance from the rotary mounting means 31 or wheel 31 which is not stabilized.

It is important to observe that the controller transmission shaft 87 coming from the compass controller enters the generator casing 33 and is journaled therein and that the rotary brush and armature supporting wheel 31 is also mounted in or journaled on the casing. Thus the mounting means 31 is placed under or in the housing frame or base plate 33 by which to carry essential parts, such as the brushes, armature and the like in opera-

tive relation with each other, and the brush or armature mounting gear 31 is disposed adjacent the armature.

One of the outstanding features which make for success of this compass is that when measuring or indicating the direction of the earth's magnetic field, no current is flowing. Hence no magneto-motive force is generated, no distortion of the earth's field occurs, and consequently no error is introduced from this source. Therefore the hand 80 of the deviation indicator 9 gives an accurate reading of the direction traveled.

What I claim is:

1. An earth inductor compass system comprising in combination with an airplane and the fuselage thereof, an instrument board mounted in the airplane for the reception of navigation instruments, a potential generating unit including brushes with mounting means supporting the brushes for adjustable turning, said potential generating unit being installed in the airplane fuselage remotely from the instrument board, power means for driving the generator, a manually operable direction controller mounted on the instrument board for adjustably turning the brushes, a graduated direction controller dial forming a part of and carried by the direction controller, a shaft and universal joint connection established between the direction controller and the remotely located potential generating unit, a deviation indicator mounted on the instrument board where it may be simultaneously observed with the aforesaid graduated dial of the direction controller, and electrical wires installed in the fuselage and connecting the potential generating unit with the deviation indicator in order that said indicator readings be effected by the remotely located generator and such affects be simultaneously observed with the manually changeable readings in terms of direction on the aforesaid direction controller dial.

2. In combination, a vehicle and electric compass system therefor comprising, a vehicle frame, a generator casing fixed on the frame, a generator carried within the casing, means for driving the generator, an adjustably turning support attached to the casing from which the generator is suspended, a direction controller mounted in the vehicle frame remotely from the generator, a graduated dial forming part of and carried on said direction controller, a shaft and universal joint connection mounted on the vehicle frame and established between the direction controller and the aforesaid adjustably turning support for adjustably orienting the generator to a new angular setting which is directly indicated by the graduated dial on the direction controller, a deviation indicator fixed on the vehicle frame remotely from the generator, and an electric transmission

line installed on the frame and connecting the separated generator and deviation indicating meter.

3. An earth inductor compass system combined with an airplane as defined in claim 1 and stabilizing means cooperating with the potential generating unit adapted to stabilize the generator in normal position and permit the airplane to move relatively thereto, whereby no current flows from the potential generating unit when the airplane is on the desired course.

4. An earth inductor compass generator comprising in combination, a base member, an adjustable turning support carried on said base member, a casing, an armature shaft journaled within said casing and projecting therethrough, an armature and a commutator carried upon said armature shaft, a gimbal joint suspending said casing from said turning support, a drive shaft journaled for rotation in respect to said base member, a universal joint connection established between said armature shaft and said drive shaft, and said drive shaft being disposed concentrically within and through the gimbal joint.

5. An earth inductor compass generator and drive unit comprising in combination, a base member, an adjustable turning support carried on said base member, a casing, an armature shaft journaled within said casing and projecting therethrough, an armature and a commutator carried upon said armature shaft within said casing, a gimbal joint connection established between said casing and adjustable turning support which gyroscopically suspends the casing and armature from the base member for stabilization of said casing and armature, a drive shaft journaled for rotation in respect to said base member, a universal joint connection made between said armature shaft and said drive shaft and being mounted concentrically within and disposed through the gimbal joint, a tube anchored to the aforesaid base member and rising vertically therefrom and enclosing the drive shaft, and driving means supported on the upper end of the tube and connected with the drive shaft for running the armature.

6. An earth inductor compass system comprising in combination, a direction controller, a deviation indicator, a generator, a mechanical connection between said direction controller and said generator, an electrical connection between said deviation indicator and said generator, a base member forming a part of said generator, an adjustably turning generator support carried by said base member, a casing, an armature shaft carrying an armature journaled within said casing, a gimbal joint connection established between said casing and said adjustably turning support, a driving shaft journaled for rotation rel-

atively to said base member, said driving shaft being normally co-axial with said armature shaft, a universal joint interposed between said driving shaft and said armature shaft, and the center of said universal joint being in substantial coincidence with the center of the above mentioned gimbal joint.

7. An earth inductor compass system comprising in combination, a direction controller, a deviation indicating steering meter, and a generator, said generator embodying a base member, an adjustable turning support adapted to rotate relatively to said base member, means cooperating with said controller for adjustably turning said support, a casing, a gimbal suspension interposed between said rotatable support and said casing, an armature shaft journaled for rotation relatively to said casing, an armature and a commutator carried upon said armature shaft within said casing, a drive shaft journaled for rotation relatively to the adjustable turning support, a universal joint interposed between said armature shaft and said drive shaft, said universal joint being substantially concentric with said gimbal suspension, power means for rotating said drive shaft, current collecting brushes carried on the casing and cooperating with the commutator, slip rings carried upon said rotatable turning support, electrical connections made between said brushes and said slip rings, current collecting brushes carried on the base member and bearing against said slip rings, and an electrical connection made between said current collecting brushes and the deviation indicating steering meter.

8. A potential generator element for electrical compass system comprising in combination, a base member, a stationary tube rising therefrom, power means carried on one end of the tube, an adjustable turning generator support carried on the other end of the tube, a generator armature having current-collecting means suspended for free universal movement beneath the adjustable turning support, a drive shaft within the tube and connected to the power means at one end, a universal connection established between the drive shaft and suspended generator, and means for adjustably turning said support.

9. A potential generator unit for electrical compass systems comprising in combination, a base member, a stationary tube rising therefrom, power means carried on one end of the tube, a gear rotatably carried on the other end of the tube, a generator armature having current collecting means suspended for free universal movement beneath the gear, a drive shaft mounted in the tube and connected to the power means at one end, a universal connection established between the drive shaft and suspended generator, and

- manually operable means for adjustably turning the gear.
10. An earth inductor compass system comprising in combination, a base member, a stationary tube rising therefrom, power means carried on one end of the tube, an adjustably turning support carried on the other end of the tube, a generator armature having current-collecting means suspended for free universal movement beneath the turning support, a shaft within the tube and connected to the motor means at one end, a universal connection established between the shaft and suspended generator, a direction controller disposed remotely from the generator, a compass dial forming part of the direction controller, means connecting the direction controller and aforesaid support adapting said support thereby to be adjustably turned by operating the aforesaid remotely located direction controller, a deviation and steering indicator, and electrical transmission wires connecting the deviation and steering indicator to the generator.
25. 11. An earth inductor compass generator comprising in combination, a cover housing by which the generator is installed in service position, a case disposed within the housing, an adjustably turned gear supported by the housing, a gimbal connection interposed between the gear and case thereby adapting the case to swing pendulously and universally free in the housing, an armature having a current-collecting means assembly carried within the pendulous case, a drive shaft, a universal joint concentrically disposed within the aforesaid gimbal connection serving to join the drive shaft and armature, power means to drive the shaft, slip rings carried on the gear, a flexible electrical connection established between the aforesaid current-collecting means and the slip rings, an adjusting shaft journaled in the housing, and a gear fixed on the adjusting shaft meshing with the aforesaid adjustably turned gear.
12. A potential generator unit for electrical compass systems comprising a base member, a casing attached to said base member, a generator armature universally supported for rotation within said casing, a stationary tubular member arising from said base member, power means carried upon said tube, a driving connection established between said power means and said armature, said power means being adjustably secured to said tube, and means provided to anchor the power means in any fixed position.
13. An earth inductor compass comprising in combination, a potential generating unit having current collecting means, said current collecting means being adjustably turned about a normally vertical axis, a manually operable direction controller located remote from said generating unit, a mechani-
- cal connection established between said generating unit and said controller whereby manual operation of said controller effects turning movement of said current-collecting means, said mechanical connection comprising a plurality of universal joints and intermediate shafts, a galvanometer deviation indicator, and electrical connection established between said current-collecting means and said deviation indicator.
14. A potential generator for electrical compass systems comprising in combination, a casing, an armature carried therein, means universally supporting the armature in the casing, a drive shaft universally connected with the armature, air impeller power means supported on the casing thereabove and connected with the drive shaft, means whereby the power means may be adjustably rotated to bring the air impeller into the line of air pressure, and means for fixing the power means in said adjusted position.
15. A potential generator for electrical compass systems comprising in combination, an adjustably turned support, an armature having current-collecting means suspended universally therefrom and gyroscopically stabilized in relation to the earth's field, means for adjustably turning the support for adjusting the current-collecting means to any desired position, means for collecting the potential and transmitting it away from the stabilized armature, a power driving head mounted above the adjustably rotatable support, a universal drive shaft connecting the power head and armature, said shaft extending concentrically through said adjustably rotatable support, and adjusting means adapted to anchor the power head in any desired position.
16. A generator for electric compasses comprising an armature and a current-collecting means assembly, means pendulously suspending said assembly, power means for driving the armature, a universal joint connection established between the power means and armature to drive the latter which simultaneously produces potential and gyroscopic force to stabilize itself in relation to the earth's field regardless of the position of the power means, and means mounted concentrically with the universal joint and mounted between the power means and armature for adjustably rotating the armature and the current-collecting means assembly in relation to the earth's field.
17. A compass generator adapted to work in the earth's field comprising, an armature and driving means therefor, a commutator and current-collecting means, rotary mounting means disposed above the armature and including means carrying the current-collecting means in operative engagement and for orientation about the commutator, and controller operating means to rotate the

mounting means by which the current-collecting means are oriented at the will of an operator to find a null-potential position for the armature.

5 18. A compass generator adapted to work in the earth's field comprising, a stationary housing support, a non-stabilized rotatable gear wheel carried with the stationary housing support, an armature and commutator 10 and means for driving them, a universally pivoted means carried with the gear wheel and pendulously supporting the armature and commutator for stabilization thereof independently of the gear wheel, current-collecting means cooperating with the stabilized commutator and including means supporting the current-collecting means on the gear wheel, a controller transmission shaft journaled in the housing support, and a gear 15 fixed on the shaft engaging the gear wheel to turn the non-stabilized gear wheel to orient the current-collecting means about the commutator.

19. An inductor compass comprising; an earth inductor generator including an armature, a commutator therefor, brushes bearing thereon, orientable-brush mounting means carrying the brushes for orientation; a deviation indicator and electrical connections 20 running therefrom to the brushes; a compass controller including a casing, a shaft journaled therein, a compass dial fixed to the shaft and mounted to turn in the casing, and drive means connected with the shaft to turn 25 it and the compass dial; and operating means connecting the compass controller with the orientable-brush mounting means whereby the compass dial and the brushes are simultaneously actuated.

40 20. An inductor compass comprising; a fieldless generator including an armature, a commutator therefor, brushes bearing thereon, orientable-brush mounting means on which the brushes are carried for orientation; a deviation indicator and electrical connections 45 extending therefrom to the brushes; operating means connected with the orientable-brush mounting means by which the latter is oriented aforesaid; a compass controller including a casing, concentrically arranged graduated compass dials mounted within the casing and connected with the operating means by which the brushes and dials are mechanically interconnected; and drive means 50 connected with the concentric compass dials and connected with the operating means by which the dials and brushes are simultaneously operated.

55 21. An inductor compass comprising; an inductor generator including an armature, a commutator therefor, current collecting means cooperating therewith, and orientable means to which the current-collecting means are attached and adapted to be oriented about 60 a normally vertical axis; a deviation indi-

cator connected with the current-collecting means; operating means connected with the orientable means and including sections of shafting; and universal joints connecting the shaft sections whereby the shaft sections are 70 operatively laid out over an angular course; and a compass controller connected with the operating means and including a casing, a shaft journaled therein, drive means to revolve the shaft, compass-dial means mounted 75 within the casing and fixed on the shaft to revolve therewith, and bevel gears connected with the shaft and connected with the aforesaid operating means whereby the orientable means and the compass-dial means are simultaneously actuated by the drive means. 80

22. An inductor compass comprising; an inductor generator adapted to run in the earth's field and including an armature, a commutator and brushes, and gear means to carry the brushes for orientation about a normally vertical axis; a deviation indicator connected with the brushes; a compass controller including a shaft, a crank fixed to one end of the shaft, direction-dial means fixed to shaft adjacent the crank, and bevel gears connected at the other end of the shaft; and operating means including shafting one end of which is connected with the bevel gears at the controller and the other end of which is operatively connected with the gear means of the generator whereby the brushes are oriented and the direction-dial means are turned when the crank is actuated. 90

30 23. An inductor compass generator comprising a gear wheel, a universally pivoted support depending therefrom, an armature pendulously suspended from the universal support, a commutator carried with the armature, brushes bearing on the armature and means carrying the brushes for orientation with the gear wheel, a drive shaft extending through the gear wheel and one end being connected to the armature to rotate the latter in the earth's field, motor means connected with the other end of the drive shaft, slip rings carried with the gear wheel and turning therewith, wire connections made between the slip rings and the brushes, contact brushes bearing on the slip rings, and means mounting the contact brushes in a stationary position. 100

40 24. An inductor generator comprising a base plate, a cover anchored thereto to house the generator parts, motor means and a support therefor on the base plate and cover, said support having one end thereof projecting through the base plate into the cover, a gear wheel inside the cover and journaled on the projecting support end, a sleeve on the gear wheel, slip rings fixed on the sleeve to rotate with the gear wheel, contact brushes fixed to the cover and engaging the slip rings; an armature, commutator and brush assembly 105 within the cover; wires connecting the slip 110 rings and the brushes. 115
